Primary Examiner — Dana L Meyrow*(74) Attorney, Agent, or Firm* — Husch Blackwell LLP(57) **CLAIM**

I claim the ornamental design for an applicator, as shown and described.

DESCRIPTION

FIG. 1 is a top perspective view of an applicator according to my new design;

FIG. 2 is a front elevation view thereof, the rear elevation view being identical;

FIG. 3 is a left side elevation view thereof, the right side elevation view being identical; and,

FIG. 4 is a top plan view thereof.

The evenly-dashed broken lines shown in the drawings illustrate the portions of the design that form no part of the claim. The dot-dash broken lines in the drawings define the bounds of the claim and form no part thereof.
